(57) **CLAIM**

The ornamental design for a guard for a beveled edger, as shown and described.

DESCRIPTION

FIG. 1 is a front, top and left side perspective view of a guard for a beveled edger showing my new design;

FIG. 2 is a left side elevation view thereof;

FIG. 3 is a top plan view thereof;

FIG. 4 is a right side elevation view thereof;

FIG. 5 is a bottom plan view thereof;

FIG. 6 is a front elevation view thereof; and,

FIG. 7 is a rear elevation view thereof.

The portions of the guard for a beveled edger shown in dotted lines do not constitute a part of the claimed design.
